(57) **CLAIM**

I claim the ornamental design for a device for holding nail polish bottle in tilted position, as shown and described.

DESCRIPTION

FIG. 1 is a perspective view of a device for holding nail polish bottle in tilted position showing my new design; FIG. 2 is a side elevational view thereof, the elevational view of the opposing side being a mirror image thereof; FIG. 3 is a top plan view thereof; FIG. 4 is an end elevational view thereof; FIG. 5 is an elevational view of the opposing end thereof; FIG. 6 is a bottom plan view thereof; and, FIG. 7 is a perspective view showing the device for holding nail polish bottle in tilted position in use; the broken lines depict environmental structure for illustrative purposes only and form no part of the claimed design.
